UNITED STATES PATENT OFFICE.

FRANCIS ECKERMAN, OF EL PASO, TEXAS.

DESIGN FOR A PENCIL GUARD AND CLIP WITH ATTACHED RUBBER.

46,649.

Specification for Design.

Patented Nov. 17, 1914.

Application filed August 10, 1914. Serial No. 856,142. Term of patent 14 years.

To all whom it may concern:

Be it known that I, FRANCIS ECKERMAN, a citizen of the United States, residing at El Paso, in the county of El Paso and State of Texas, have invented a new, original, and ornamental Design for Pencil Guards and Clips with Attached Rubber, of which the following is a specification, reference being had to the accompanying drawing, forming part thereof.

Figure 1 is a rear elevation of a pencil

guard and clip, with attached rubber, showing my new design; Fig. 2 is a front elevation; and Fig. 3 is a side elevation.

I claim:

The ornamental design for a pencil guard and clip, with attached rubber, as shown.

FRANCIS ECKERMAN.
